DRAFTING COMPASS OR THE LIKE

Clinton N. Eason, 3318 Suffolk, Houston, Tex.

Filed May 19, 1964, Ser. No. 80,063

Term of patent 14 years

(Cl. D52—6)

FIG. 1

FIG. 2

FIGURE 1 is a plan view of a drafting compass embodying my new design, and

FIGURE 2 is a vertical sectional view thereof.

The rear of the drafting compass is plain in appearance.

The essential features of the design reside in the solid line portions of the drawing.

I claim:

The ornamental design for a drafting compass or the like, substantially as shown and described.
